CLAIM

(51) **LOC (10) Cl. 07-02**

The ornamental design for a spatula head with mixer blade
scraper, as shown and described.

(52) **U.S. Cl.**

DESCRIPTION

USPC **D7/688**

(58) **Field of Classification Search**

FIG. 1 is a top perspective view of the spatula head with mixer
blade scraper;
FIG. 2 is a top plan view thereof;
FIG. 3 is a bottom plan view thereof;
FIG. 4 is a right side elevation view thereof;
FIG. 5 is a left side elevation view thereof;
FIG. 6 is a front elevation view thereof; and,
FIG. 7 is a rear elevation view thereof.
The broken lines represent portions of the article and form no
part of the claimed design.
